IMPRINTED PAPER

Filed Dec. 21, 1925

Fig. I.

Fig. II.

DANIEL D MADDEN,
Inventor,

By *newright.*

Attorney.

UNITED STATES PATENT OFFICE.

DANIEL D. MADDEN, OF PORTLAND, OREGON.

IMPRINTED PAPER.

Application filed December 21, 1925. Serial No. 76,807.

My invention relates to imprinted papers, an article of manufacture, as a class. One feature of my invention relates to paper particularly adapted for wrapping purposes with an imprinted background and imprinted designs, characters or labels thereon all resulting from a single coloring liquid pressed into the paper with different degrees of pressure thus producing a printed background and a differently tinted design or character the same being the result of a single imprint after immersion in the colored liquid bath. This feature, as well as others, I attain as shown in the drawing which forms a part hereof.

Fig. I is a plan view of the obverse side of a portion of a sheet or roll of the manufactured paper.

Fig. II is a plan view of a like portion showing the reverse side thereof.

Like characters refer to like parts in the views.

The paper 1 has a primary lightest tint 2 which is the same as that of the bath in which it is immersed. The second tint 3 is a background printed about the label, characters or design, and the third tint 4 forms a body tint surrounding the design background and its margin. As the paper illustrated is preferably printed or colored by use of a process which I now employ, the same will be explained. A bath is provided and in connection therewith is a roller apparatus, consisting of a lower roller and an upper opposing roller with mechanism to compress the rollers into snug engagement with each other. The lower roller is of some resilient material. The upper one is of metal and has circumferential recesses therein. Plates having a design or characters engraved thereon of similar kind to that shown in the figures are secured in the roller recesses with a margin left about the plates. These plates are secured with their surfaces a pre-determined slight distance beyond the surface plane of the rollers. A selected color liquid is placed in the bath. The surface of the liquid is generally below the roller intake. The paper, in strip rolls, is passed into the bath and immersed so as to absorb the liquid throughout its texture and passes from the liquid between the rollers and thence preferably between wringer rollers outwardly to a drying place. As the paper, saturated with the color liquid, passes through the imprinting rollers, the portion thereof over the engraved design or characters, and the margin, being where the tint 2 is shown, is not engaged by the rollers or plates, and the tint 2 remains like that of the bath liquid. The plates, extending beyond the roller surface plane, imprint a darker background tint 3 about the design. The remainder of the roller surface plane, exerting a diminished pressure upon the paper, imprints a tint 4, lighter than tint 3 and darker than the bath tint 2. The making of all three tints from a single coloring liquid occurs simultaneously as the paper passes through the imprinting rollers. The process is extremely rapid, economical and efficient. The paper thus manufactured is of very attractive nature and affords an unlimited field for advertising by those using wrapping paper, and at an economical price. The article has been manufactured, proven to be practical and has been readily and extensively accepted by users as a new and useful article in the art and trade, and such it is.

I claim:

A paper dyed throughout its structure and having a dyed design thereon, differing in its color appearance from the rest of the dyed paper surface, the paper having the dye pressed into it over approximately its whole surface with the same dye in the design as in the rest of the paper, but with different degrees of pressure, said design being visible on both surfaces of the paper.

DANIEL D. MADDEN.
